UNITED STATES PATENT OFFICE.

JOHN R. WARREN, OF GRAND RAPIDS, MICHIGAN, ASSIGNOR TO HIMSELF, DONALD J. CAMPBELL, OF MUSKEGON HEIGHTS, MICHIGAN, AND CHARLES E. JOHNSON, PAUL R. BEARDSLEY, AND CARL P. DAMM, TRUSTEES, ALL OF MUSKEGON, MICHIGAN.

GUIDING DEVICE.

Application filed November 15, 1923. Serial No. 674,882.

To all whom it may concern:

Be it known that I, JOHN R. WARREN, a citizen of the United States, residing at Grand Rapids, in the county of Kent and State of Michigan, have invented new and useful Improvements in Guiding Devices, of which the following is a specification.

The present invention relates to guiding devices, particularly such as may be employed to guide a cylinder, of an internal-combustion engine, having a longitudinal movement relatively to the rotary valve of such engine; and its object is to provide such a device capable of being so positioned as to accurately guide the guided member of the mechanism and to be securely held in its accurately-guiding operation against dislocating movement.

This and any other objects hereinafter appearing are attained by, and the invention finds preferable embodiment in, the structure hereinafter particularly described in the body of this specification and illustrated by the accompanying drawings, in which:

Figure 1 is a side view of an internal-combustion engine of the four-cycle type, having six cylinders, three of which and the engine's frame are shown partially sectioned in a diametrical plane of the cylinders, to which engine my guiding device is applied;

Figure 2 is a transverse sectional view of the upper portion of the same taken on line 2-2 of Figure 1;

Figure 3 is a sectional view of the guiding device and adjacent parts taken on line 3-3 of Figure 4;

Figure 4 is a sectional view of the same taken on line 4-4 of Figure 3;

Figure 5 is a view thereof sectioned on line 5-5 of Figure 4;

Figure 6 is a sectional view of parts of the same taken on line 6-6 of Figure 4;

Figure 7 is an outer end view of a guide means;

Figure 8 is an opposite end view thereof; and

Figure 9 is a side view of the same.

In the embodiment of the invention chosen for illustration by the drawings and for detailed description in the body of this specification, my guiding device is shown applied to an internal-combustion engine of the four-cycle type having six cylinders, 1, 2 and 3 thereof appearing partially sectioned

diametrically in Figure 1, three cylinders 55 being formed in each of the two cylinder blocks 4, and the cylinders having pistons and connecting rods 7 for operating the cranks respectively on the crank shaft or engine shaft 6. At their upper ends, the 60 cylinders have ports 61 for the admission of the operating fluid thereinto and for the expulsion of the products of combustion therefrom. The rotary valve 15, for controlling the admission of the operating 65 fluid to the cylinders and for permitting the expulsion of the products of combustion therefrom, rotates in a bearing or valve chamber in a split valve-casing designated 70 generally 16, having ports communicating 75 through the cylinders' said ports respectively, such valve-casing comprising an upper portion 8 supported in connection with the engine frame 14 and a lower portion 9 supported in connection with the cylinders of 80 the cylinder blocks. These cylinder blocks have a slight movement in the cylinders' longitudinal direction in bearings 10 on the frame, such movements being caused by varying pressures in the cylinders as explained in Patent No. 1,449,469 issued March 27, 1923 on my application.

In the construction shown, the valve-casing 16 has a bushing 34 surrounding the valve non-rotatively and provided with 85 openings 35 which register with the cylinders' ports respectively. The valve is hollow, having longitudinally-extending passages (not shown) to which the fluid is supplied from a vent 26 in the frame, the fluid thence passing through a series of inlets 51 through the valve's wall and to each cylinder's port through openings 28 in the valve's wall, the products of combustion being discharged from each cylinder through outlets 30 through the valve's wall and into its longitudinally-extending passage 32 opening at the end or ends of the valve through a centrally-disposed outwardly-extending exhaust nozzle 11 communicating with the 90 exhaust pipe 53.

It is evident that when, in the cycle of the engine's operation, the firing stroke occurs in cylinder 1, the cylinder block 4 is not only pressed upwardly toward the valve for a slight distance in its bearings 10, but its lower end is pressed toward the right-hand side of Figure 1, a rocking movement about 100

an axis extending horizontally through the cylinder block in the transverse direction of the valve thus taking place with the alternate firing strokes in cylinders 1 and 3.

5 In the application of my guiding device shown in the present example, this rocking movement is resisted and the slight longitudinal movement of the cylinders may be trued to the proper line. In this example, 10 the cylinders 1, 2, 3 are provided with one or more (two in the construction shown) downward extensions or members 12 movable with the cylinders and guided by my device. This device comprises guide members or blocks 13 movable relatively to a fixed member—the engine frame 14—in a direction inclined to the movement of the cylinders (i. e. of the members 12), means being provided for securing blocks or guide members 13 in desired adjusted position against said inclined movement, such means in the construction shown being a threaded clamping bolt. To effect this inclined movement into its adjusted position and to secure 25 the guide member in said position, it is provided with a slide bearing 17 extending in the line of its said inclined movement, fixed guide means extending into and slidably bearing in said bearing. As particularly 30 shown in Figures 3, 4, 6, 7, 8 and 9, the fixed member (the engine frame 14) has an opening 18 through which the guide means, a cylindrical plug 19 rotatably fitting in said opening, extends. This guide means 35 has a flattened inner end portion 20, slidably guidingly fitting in the slide bearing 17, and has an axially extending opening 21 through which extends the clamping bolt 22 screw-threaded in the block or guide member 13, 40 and a head 23 outside the frame 14, whereby the bolt may be screwed down to clamp the flange 24 of the cylindrical guide means and the guide member 13 securely to the frame 14. The opening 21 in the guide means 19 45 is elongated as seen in Figures 4, 6, 7 and 8 to permit the movement of the block 13 in the aforesaid inclined direction to its adjusted position.

It will be understood that when the 50 blocks 13 are moved to and secured in their adjusted position, they cannot be moved therefrom by the movement of the cylinders and vibrations of the machine, owing to the acute angle between the cylinders' longitudinal movement and the bearing 17 of the 55 guide blocks 13; and that the adjustment of these guide blocks may be made from outside the engine frame 14; and it is also evident that my guiding device may be employed in connection with other mechanisms as well as with that illustrated by the drawings.

The invention being intended to be pointed out in the claims, is not to be limited to or by details of construction of the particular embodiment thereof illustrated by the

drawings or hereinbefore shown or described.

I claim:

1. In a guiding device: a movable member; a member fixed relatively thereto; a pair of guide members slidably contacting the opposite sides of the movable member for guiding the same and movable relatively to the fixed member in a direction inclined to the movable member's movement; means 70 for securing the guide members against movement relatively to the fixed member.

2. In a device of the character described: a movable member; a member fixed relatively thereto; a pair of guide members 80 slidably contacting the opposite sides of the movable member for guiding the same and having slide bearings inclined to the direction of the movable member's movement; guide means slidably bearing in the guide 85 members' bearings; means for securing the guide members against movement relatively to the fixed member.

3. In a device of the character described: a movable member, a member fixed relatively 90 thereto and having an opening; a guide member for guiding the movable member and having a slide bearing inclined to the direction of the movable member's movement; guide means for guiding the movable member; a bolt extending through said opening and in threaded relation with the guide 95 member.

4. In a device of the character described: 100 a movable member; a member fixed relatively thereto and having an opening; a guide member for guiding the movable member and having a slide bearing inclined to the direction of the movable member's movement; guide means extending through 105 said opening and slidably bearing in the guide member's bearing and having an opening; a bolt extending through the guide means' opening and in threaded relation with the guide member, and adapted to 110 clamp the guide member, guide means and fixed member together.

5. In a device of the character described: 115 a movable member; a member fixed relatively thereto and having an opening; a guide member for guiding the movable member and having a slide bearing inclined to the direction of the movable member's movement; guide means extending through and 120 rotatably bearing in said opening and slidably bearing in the guide member's bearing and having an opening; a bolt extending through the guide means' opening and in threaded relation with the guide member, and adapted to 125 clamp the guide member, guide means and fixed member together.

In testimony whereof I have hereunto set my hand at Grand Rapids, Michigan, this 5th day of November, 1923.

JOHN R. WARREN.
